UNITED STATES PATENT OFFICE.

WILLIAM Y. BUCK, OF MUNCIE, INDIANA.

HOLDER FOR ELECTROPLATING.

No. 889,103.

Specification of Letters Patent.

Patented May 26, 1908.

Application filed September 25, 1907. Serial No. 394,494.

To all whom it may concern:

Be it known that I, WILLIAM Y. BUCK, of Muncie, in Delaware county, in the State of Indiana, have invented certain new and useful Improvements in Holders for Electroplating, which improvements are described in the following specification and are illustrated by the accompanying drawings.

This invention relates in general to that method of electroplating which consists in holding between two anodes in an electrolytic bath separate pieces of work, facing toward and near each other, and in passing current from the anodes through the plating solution to the work, while held in that position; and relates in particular to apparatus which is used in electroplating by that method for the purpose of holding, in the plating solution, spoons, forks and other articles of flat ware, which are to be plated unequally upon opposite sides.

It is the object of the invention to facilitate the placing of such articles in their appropriate positions in such a holder; to hold those articles in their proper attitudes invariably, and without danger of turning or facing about; to promote an automatic return of the same to their predetermined positions, whenever slightly displaced by accident; to prevent markings upon the work, where it touches the holder; to diminish electrodeposition upon the holder, and at the same time to increase the inequality of deposit upon opposite sides of the work. To accomplish these objects I incorporate in the holder an indefinite number of connected and partly insulated wire loops, which are of a peculiar pattern, and are peculiarly positioned.

In the accompanying drawings, Figure 1 is an end elevation of my improved holder, with spoons therein, all in working position in an electroplating vat. Fig. 2 is a perspective view of the upper portion of the same holder. Fig. 3 is a horizontal section on line $x-x$ of Fig. 2. Fig. 4 is a vertical section on the line $y-y$ of Fig. 2.

In these drawings, a single loop, for a single piece of work, is denoted by the numeral 1. As shown in Fig. 3, this loop consists of two wires, 2 and 3, which form its boundary, and are twisted together at each end of the loop to form its terminal connections. Being approximately flat, it has the form of an irregular and curvilinear parallelogram, whereof one side 2 is formed by wire 2, while the opposite side 3 and the ends 4 are formed by

wire 3. Side 2 curves symmetrically a little outward near the middle, and side 3 a little inward, so that the opening between them, as seen from above, conforms rudely with the shape of the work, which is seen in cross-section in the same Fig. 3. The ends of the loop are rounded out in the middle, so that the opening between them is longest between the points which are indicated by the numerals 60 4. Wire 3 is preferably of steel, while wire 2 is either made of nonconductive material or thoroughly insulated with a covering of that character. Wire 3 is similarly insulated in those portions only which form no part of the 65 loops.

Excepting the loops and wires 1, 2 and 3, the frame of the holder consists of a pair of vertical side bars 6, which are united by an arched handle 5, and are provided, at different levels, with pairs of horizontal and parallel cross-bars 7, all formed of coarse and electrically conductive wire, preferably of steel. In the side bars of this frame are formed two hooks, or bends, 8, by which the 70 device may be suspended in the usual manner. At these points of support, the frame is provided with copper contact pieces, which are applied to the frame in the form of close-fitting sleeves, before bends 8 are formed. 75 Below these points of support, the side bars 6 and the cross-bars 7 are insulated with a coating of vulcanized rubber, porcelain, or other nonconductive material, which will protect the coated surfaces from all deposit, and will 80 receive no deposit upon itself. 85

The cross-bars 7 of each pair are connected by two parallel and duplicate chains of loops 1, the latter being formed of wires 2 and 3 as described, and being connected with each 90 other by intermediate portions 9 of the same wires, twisted together, as shown in Fig. 2. The ends of these chains are soldered to the ends of cross-bars 7, the loops 1 being placed in inclined positions, as shown in Fig. 4, 100 where the front portion of the loops is plainly shown tipped obliquely downward.

In Fig. 1 the numerals 10 denote the side walls of a vat, containing a plating solution 11, in which the work is suspended. The 105 anodes 12, being plates of silver or other metal, are submerged in the solution at a little distance from the work, on opposite sides of the holder, being supported by hooks 13, which are in electrical contact with a copper 110 strap 14, representing the positive pole of the current generator.

In the operation of my invention, the work, which is represented by spoons 15, is placed in position in the holder in the following manner: The handles 16 of the spoons are first inserted from above in the several loops 1, and are permitted to descend therein till stopped by contact of the spoon bowls 17 with the end wires 4 of those loops; then, being aided or propelled by gravitation, and being guided by the bulging and sloping ends 4 of the loops, the spoons 15, either automatically, or aided by a little shaking of the apparatus by hand, settle down into the precise position which is indicated in the drawings. In that position they seek to remain, and to that position they tend to return in the same manner, as often as they are disturbed. Resting or swinging in that position, they are severally supported in their respective loops by edge contacts only, as shown in Fig. 3; and hence receive no wire marks while being plated.

In each loop 1, the back wire 4, being bent outward, leaves ample room for the accommodation of bowl 17, as it swings in the motion of the vat; and, being insulated, leaves the solution wholly unimpoverished, where it comes in contact with the back of the work; at the same time, the front of the loop, being bent inward as described, prevents the work from turning or facing about; and the loop ends 4, being divergent, curved and sloping, as described, not only throw the work forward into the position indicated in the drawings, but also prevent the same from catching and binding in the corners of the loops, where the wires 3 and 4 come together. On the same holder, the deposit, being limited to a portion of each loop, is practically equal only to the insignificant deposit laid on the work during the loading and unloading of the vat, and hence may be entirely disregarded; so that the weight of metal deposited on the work, may be determined at any time

from the weight of the holder and work together, as observed before and after exposure in the plating solution.

I claim as my invention—

1. In a holder for electroplating, a pair of insulated conductive bars, which are provided with a connecting handle and with suspensory hooks, in combination with a pair of insulated, parallel and normally horizontal cross-bars, which are rigidly and conductively united with said conductive bars respectively, and a number of work-engaging loops, which are formed by and between two wires, namely: an insulated or non-conductive back wire, bent outward from the middle of each loop, and an exposed conductive front wire, bent inward at the front of each loop, and bent divergently outward at the ends of each loop, said wires being twisted together between said loops, and said loops being arranged in duplicate, parallel and inclined chains, connecting said crossbars.

2. In a holder for electroplating, a pair of insulated side bars, which are united by a handle, and are provided with conductive hooks, in combination with two conductive and insulated crossbars, which are separately united with said side bars respectively, and work-engaging loops, which are severally formed by and between two wires, viz.: an insulated or non-conductive back wire, bent outward from the middle of each loop, and an exposed conductive front wire, bent inward at the front of each loop, and bent outward at the ends of each loop, said loops being connected by said wires, twisted together, and being arranged in duplicate chains, connecting said cross-bars.

In testimony whereof I hereunto set my name in the presence of two witnesses.

WILLIAM Y. BUCK.
